COMBINED MOLDED CONTAINER AND COVER THEREFOR

Arthur Ringlen, New York, N.Y., assignor to J. E. Plastics Manufacturing Corp., Yonkers, N.Y., a corporation

Filed Jan. 3, 1961, Ser. No. 63,428

Term of patent 14 years

(Cl. D58—12)

FIG. 1

FIG. 2

FIG. 4

FIG. 1 is a top view of a cover of a combined molded container and cover therefor, showing my new design;

FIG. 2 is a bottom plan view thereof;

FIG. 3 is a side elevational view thereof; and

FIG. 4 is a cross-sectional view taken on line 4—4 of FIG. 3.

The characteristic feature of my design resides in the combination on the covered container disclosed of the regular fluting on the sides of the container which terminate in a hollow square on the bottom portion, the corner flutes forming posts within the art of L shaped extensions connecting the adjacent side flutes, all as shown.

I claim:

The ornamental design for a combined molded container and cover therefor, substantially as shown and described.
